COMPENSATING CIRCUIT

Donald D. Grieg, Forest Hills, N. Y., assignor to
 Federal Telephone and Radio Corporation, New
 York, N. Y., a corporation of Delaware

Application May 19, 1944, Serial No. 536,302

2 Claims. (Cl. 179—171.5)

1

This invention relates to electrical circuits and more particularly to such circuits utilizing electron control tubes such as pulse modulator circuits.

There are occasions when a relatively unstable source of voltage only is available for electrical apparatus such as a radio transmitter. This usually results from necessity rather than choice, as in the case of equipment for installation on airplanes or in portable sets where the addition of voltage regulators would cause an undesirable or even prohibitive increase in weight. As a consequence of the random fluctuations in the available voltage supply in such cases, the output of energy from the apparatus is likewise caused to vary, thereby producing distortion in the speech or other intelligence being transmitted.

While a varying voltage supply of the above nature is undesirable in conventional amplitude modulation transmitters, such a condition becomes an even greater factor in pulse transmitters of the time modulation type. In the latter, any variation in the voltage supply results in an undesirable variation in pulse spacing or position. Since the maximum time displacement of the pulses in time modulation systems is usually very small compared to the spacing between successive pulses, it will be clear that even a slight change in the amplitude of the voltage source will cause a pulse time shift that is appreciable in comparison with the signal modulation and therefore undesirable.

It is accordingly an object of the present invention to provide means for compensating for the effect of supply voltage fluctuations in circuits including electron discharge devices.

It is a further object of the invention to provide means for varying the modulator grid bias in an oscillator-modulator circuit of the pulse time modulator character in such a manner as to compensate for variations in the common supply voltage of such circuits.

Other objects and advantages of the invention will be apparent from the following detailed description to be read in connection with the accompanying drawings, in which:

Fig. 1 is a circuit diagram of one form of time modulator incorporating the principles of the present invention;

Figs. 2A, 2B and 2C are curves useful in explaining the operation of the circuit of Fig. 1; and

Fig. 3 is a circuit diagram of a modification of the form of the invention illustrated in Fig. 1.

In Fig. 1 is shown a source of unregulated volt-

2

age 1 which comprises a generator driven by a variable speed motor as in case of aircraft or by other means the speed of operation of which is difficult to control. The voltage of source 1 is applied across a voltage divider 2. An oscillator 3 of any suitable type has its plate voltage supplied from an adjustable tap 4 on voltage divider 2 through a connection 5. As a result of the oscillator 3 being supplied with plate voltage from source 1, the output of the oscillator will vary in proportion to the value of the voltage supply, or, in other words, the voltage output of the oscillator 3 will vary linearly with respect to a variation in the voltage from source 1.

A modulating circuit generally indicated at 6 is coupled to the oscillator 3 by means of transformer 7 having a primary coil 8 and two secondary coils 9 and 10. The primary coil 8 of the transformer 7 forms part of the plate tank circuit of the oscillator 3. The two secondary coils 9 and 10 have their outer terminals respectively connected to the grids 11 and 12 of two triodes 13 and 14, which as shown, may be enclosed in a common envelope. The plate voltage for the anodes of triodes 13 and 14 is supplied from an adjustable tap 15 on voltage divider 2 over a common connection 16.

The inner terminals of each of secondary windings 9 and 10 of transformer 7 are connected to the ends of the primary winding of an audio transformer 17. The midpoint of this primary winding is grounded. The voltage for the speech circuit portion of the modulator 6, including microphone 18 and the secondary winding of transformer 17, is derived across voltage divider 2 by means of a third adjustable tap 19.

From the above description, it will be seen that a common voltage supply is provided for the oscillator 3, the plate circuit of modulator 6 and the audio circuit including microphone 18. Since a change in the potential of source 1 will result in a drop in the voltage across voltage divider 2, it can be seen that any change in the supply voltage will produce proportional changes in the voltages taken off by adjustable taps 4, 15 and 19. Thus the voltages in the three above-mentioned circuits will at all times vary concurrently and in proportion to one another.

These corresponding variations however do not compensate one for the other as regards the output of the circuit. A further compensating effect must be provided in order to prevent the variation of voltage source from affecting the circuit output. I accomplish this desired effect by providing a biasing circuit which varies in response

to variation in the voltage source. The biasing circuit includes a cathode resistor 20 connected between the cathode 21 of tube 14 and ground, a further resistor 22 connected between the upper terminal of resistor 20 and the cathode 23 of triode 13. A pair of conventional by-pass condensers 24 and 25 respectively shunt the resistors 20 and 22 to ground.

The operation of the circuit disclosed in Fig. 1 will be easily understood by considering the curves of Figs. 2A, 2B and 2C. Each of the triodes 13, 14 is designed to have substantially identical operating characteristics, such as shown by the common characteristic operating curve 26 of Fig. 2A. It is preferable that the tubes be designed to have a sharp cut-off, such as the point 27. The operating curve 26 of Fig. 2A represents the normal operating curve of tubes 13 and 14 for a certain steady potential applied to the respective anodes thereof. Resistors 20 and 22 are so chosen that the bias between grid 12 and cathode 21 of triode 14, on one hand, and the bias between grid 11 and cathode 23 of triode 13, on the other hand, will be substantially equal on opposite sides of the cut-off point 27 as indicated in Fig. 2A.

The wave produced by oscillator 3 is applied through transformer 7 to the two secondary windings 9 and 10. This makes the outer terminal of winding 9 180° out of phase with the outer terminal of winding 10. Thus the wave of oscillator 3 will be applied on grids 11 and 12 one inverted in phase with respect to the other.

Due to the difference in absolute bias between tubes 13 and 14, different portions of the input waves to the grids 11 and 12 will be passed by the tubes. If the wave input to tube 14 is designated as 28 and the wave input to tube 13 is designated as 29, then it will be seen that waves 28 and 29 will intersect at unequally-spaced points 30, 31, 32 and 33 along a linear vertical axis 34 which intersects the characteristic curve 26 at cut-off point 27. While waves 28 and 29 are shown for illustration purposes as triangular in shape, it will be understood, of course, that they will be sinusoidal from oscillator 3. If desired, the input waves may be made triangular by suitable shaper circuits.

When the two waves 28 and 29 are projected against the characteristic curve 26, the wave output will be as represented in Fig. 2A. It will be noted that the spacing of the peaks 30, 31, 32 and 33 is similar in the output curve of Fig. 2A as was the spacing of the corresponding points along the axis 34. If desired, a suitable clipping and differentiating circuit can be provided in the output of modulator 6 so that the peaks at points 30, 31, 32 and 33 will be transformed into a train of pulses having the spacing represented by such points. Where sinusoidal waves are used at the input, the peaks are in the form of cusps which when clipped provide sharp pulses.

The audio modulating circuit including microphone 18 and transformer 17 is connected as above described to the inner terminals of each of secondary coils 9 and 10 of transformer 18. By means of this connection a variation in the current through transformer 17 due to the reception of sound by microphone 18 will vary the current in the windings 9 and 10. This will cause the waves 28 and 29 of Fig. 2A to be, in effect, shifted relative to their respective zero or bias 34 and 35, and this in turn will change the relative spacing between pulse position points 30, 31, 32 and 33. As a result of the direction of flow of current

in windings 9 and 10, the shift in waves 28 and 29 is simultaneously toward or away from axis 34. This causes successive points 30, 31, 32 and 33 to be displaced in opposite directions in "push-pull" manner for each cycle of the audio signal. Thus there is obtained a time modulation of the peaks 30, 31, 32 and 33 in accordance with the voice or other intelligence intercepted by microphone 18.

10. The above description of operation has been made upon the assumption that the voltage from source 1 remains at a steady value. Assume now that for some reason this voltage undergoes a random fluctuation amounting to a drop of one-third in absolute value, the bias on triodes 13 and 14 remaining as before. The results of such a fluctuation are illustrated in Fig. 2B. As seen in this figure, the characteristic curve of the triodes 13 and 14 has dropped from position 26 to a new position 36. The amplitude of the wave output from oscillator 3 has decreased proportionally, that is, to two-thirds of its former value. With the biases 34 and 35 unchanged, the projection of waves 28a, 29a against the new operating curve 36 will produce the output shown. Points 30, 31, 32 and 33 will assume new positions 30a, 31a, 32a and 33a; the amplitude of waves 29a will be decreased considerably from its input value, and wave 28a will not be passed to any degree. As a result, the time displacement of points 30a, 31a, 32a and 33a will vary considerably with respect to the original spacing as shown in Fig. 2A. In other words, the output of the modulator 6 will be distorted to a very considerable degree so as to reduce the fidelity of transmission.

In order to correct the distortion resulting from the operation of the circuit of Fig. 1 as shown in Fig. 2B, the resistors 20 and 22 employed in connection with the triodes 13 and 14 are so chosen that a change in plate current resulting from a change in voltage from source 1 will produce a drop across resistor 20 that is proportional to this change in current for triode 14 and a proportional change in voltage across the resistor combination 20, 22 for triode 13.

The result of utilizing such a combination of resistors is illustrated in Fig. 2C. Fig. 2C retains the new operating curve 36 of Fig. 2B, but the biases on triodes 13 and 14 have each dropped one-third in value, and have shifted to new position 35a and 34a. It should be emphasized that the change in the value of biases 34a, 35a is proportional to the voltage fluctuation in source 1, and consequently to the change in current in the plate circuit. Fig. 2C also illustrates the effect of projecting the reduced amplitude waves 28a and 29a symmetrically disposed on their new biases 34a and 35a respectively, against the new operating curve 36. It will be seen that while the amplitude of the resulting output signal is reduced the points of intersection of output waves 28a, 29a are identical with those shown in Fig. 2A, that is pulse positions 30, 31, 32 and 33 are time displaced in amount substantially equal to that shown in the normal operation curve 2A.

Thus it is seen that by the use of a compensating or self-regulating arrangement including the resistors 20 and 22, it is possible to maintain substantially constant the time displacement of the pulse positions 30, 31, 32 and 33 representing the points of intersection of the input waves 28 and 29, thus avoiding any distortion which might result in a shift in these points as shown in curve 2B when compensating means is lacking.

Condensers 24 and 25 should be large enough to smooth pulsations in the cathode circuit across resistors 20 and 22.

Since the audio energy is supplied through adjustable tap 19, the audio modulation through transformer 11 will vary proportionally to the amplitude of the base wave from oscillator 3. Thus the relative modulation of the base wave by the audio wave will remain constant regardless of variation in voltage from source 1.

While the variation in source potential has been shown in the curves of Figs. 2A, 2B and 2C as a voltage drop, it should be clearly understood that this has been selected merely as an example, and that the theory of operation is similar in all respects for an increase in voltage as for a decrease.

Fig. 3 illustrates a modification of Fig. 1 employing an additional resistor 37 connected between junction point 38 on lead 16 and the top terminal of resistor 22. This additional resistor 37 is of a high value, and acts to produce the desired bias voltage across resistors 20 and 22 independently of the operating conditions of triodes 13, 14. This modification of Fig. 3 maintains a constant D. C. potential across resistors 20, 22 regardless of the A. C. current through triodes 13 and 14. When the resistor 37 is utilized, a separate load resistor 39 is preferably employed between the output of the triodes and connection point 38.

While I have described above the principles of my invention in connection with specific apparatus, and particular modifications thereof, it is to be clearly understood that this description is made only by way of example and not as a limitation on the scope of my invention as set forth in the objects of my invention and the accompanying claims.

I claim:

1. In a time modulation system of the type including an oscillator and balanced modulator fed from a common source of unregulated voltage, in which the balanced modulator includes two

electron discharge devices each having an anode, cathode and grid, a biasing arrangement for producing an initial differential bias on the two devices and while maintaining said differential varying the mean bias of said devices to compensate for variation in the voltage of said source comprising a first biasing resistor connected in series between the cathode of one of said electron discharge devices and the negative side of said source of potential, and a second biasing resistor connected at one end in series with said first resistor to the negative side of said source of potential and at its other end to the cathode of the other of said electron discharge devices.

2. A time modulation system according to claim 1, further including an arrangement for translating mechanical signals into electrical signals, means for coupling said arrangement in push-pull to the grids of said electron discharge devices, and a circuit for supplying said arrangement with potential from said source of potential.
